Primary Examiner — Susan Bennett Hattan*Assistant Examiner* — Elizabeth S Ko(74) *Attorney, Agent, or Firm* — Schultz & Associates,
P.C.(57) **CLAIM**

The ornamental design for a tap, as shown and described.

DESCRIPTION

FIG. 1 is a perspective view of a tap, showing my design; FIG. 2 is a front elevation view thereof, showing my design; FIG. 3 is a rear elevation view thereof, showing my design; FIG. 4 is right side elevation view thereof, showing my design; FIG. 5 is a left side elevation view thereof, showing my design; FIG. 6 is a top plan view thereof, showing my design; and, FIG. 7 is a bottom plan view thereof, showing my design. The broken lines in the drawings depict parts of the tap that form no part of the claimed design.

1 Claim, 2 Drawing Sheets(56)
